FILM DEVELOPING HOLDER

Louis E. Davis, Fort Smith, Ark.

Application December 7, 1936, Serial No. 114,703

4 Claims. (Cl. 95—100)

This invention appertains to new and useful improvements in means for holding dental X-ray films while being developed.

The principal object of the present invention is to provide a simple and inexpensive holder whereby a multiplicity of dental X-ray films can be held simultaneously in position for developing.

Another important object of the invention is to provide a holder of the character stated where-
10 in the various parts are readily separable and at-
tachable together as required.

These and numerous other important objects and advantages of the invention will become ap-
parent to the reader of the following specification.

15 In the drawings:—

Figure 1 represents a side elevational view of the device.

Figure 2 is a horizontal sectional view on the line 2—2 of Figure 1.

20 Figure 3 is a vertical sectional view through the device taken substantially on the line 3—3 of Figure 1.

Figure 4 is a fragmentary vertical sectional view.

25 Figure 5 is an end elevational view of the holder showing only one of the carriers in place.

Referring to the drawings wherein like numerals designate like parts, it can be seen that Figure 3 shows three of the magazines or car-
30 riers and these are generally referred to by nu-
merals 5, 6 and 7.

Each of these magazines consists of a pair of end walls 8—8 connected by the angle iron members 9—9 at their lower corners and further
35 connected by a pair of horizontally spaced trans-
versely corrugated strips 10—10. These strips are corrugated so as to provide opposed groove-
ways for the reception of the vertical edge por-
tions of the dental X-ray films 11.

40 The lowermost magazine 5 has the lower ends of the leg portions 12—12 secured to its rear angle bar 9. These leg members 12—12 are part of the single strand handle constructed of spring rod or wire material and formed to provide a handle or hook structure 13 at its upper end.

45 Secured to the rearmost angle bar of each of the magazines 6—7 is a plate 14 which has in-
wardly bent end portions 15 defining hooks for the reception of the leg portions 12—12.

50 In other words the bail 16 of the lower maga-

zine 5 can be swung over the same to engage in the notches 17 of its end plates 8 after which the magazine 6 can be placed upon the magazine 5 and the legs 12 contracted and engage against the plate 14 on the magazine 6 and subsequently released so as to engage with the hooks 15 thereof. The magazine 7 is fastened in place in the same manner and, of course, the bails 16 are engaged over the films 8 so as to prevent displacement of the same when immersed in the developing 10 solution.

While the foregoing specification sets forth the invention in specific terms, it is to be understood that numerous changes in the shape, size and materials may be resorted to without departing 15 from the spirit and scope of the invention as claimed hereinafter.

Having described the invention what is claimed as new is:—

1. A holder of the character described com-
prising a magazine structure, a hanger consist-
ing of a pair of spring leg members and a head
portion and a hook structure on one side of the
said magazine into which the spring leg members
of the hanger can be engaged for tensionally se-
curing the magazine to the hanger. 20

2. A holder of the character described com-
prising a magazine structure, a hanger consist-
ing of a pair of spring leg members and a head
portion and a hook structure on one side of the
said magazine into which the spring leg members
of the hanger can be engaged for tensionally se-
curing the magazine to the hanger, and a second
magazine having the lower ends of the said leg
members permanently secured to one side thereof. 25

3. A holder of the character described com-
prising a magazine, a hanger having its lower end
secured to the magazine, and a bail adapted to
be swung over the said magazine to prevent dis-
placement of articles therein. 30

4. A holder of the character described com-
prising a magazine, a hanger for the magazine,
said magazine being provided with a pair of lon-
gitudinally extending and horizontally spaced
corrugated strips defining opposed grooveways
for the reception of the edge portions of verti-
cally disposed sheet articles disposed in the
magazine. 35

LOUIS E. DAVIS. 50
